1. Reproductions **1.1** to **1.7** are front perspective, front, back, left, top, bottom and back perspective views of the cart for wearable walking aid apparatus in a condition that the claimed design has been completely folded. Reproductions **1.8** and **1.9** are reference photos showing the condition that the claimed design has been completely folded and the user is sitting thereon, and form no part of the claimed design. Reproductions **1.10** to **1.16** are front perspective, front, back, left, top, bottom and back perspective views thereof in a condition that the claimed design has been half unfolded. Reproductions **1.17** to **1.23** are front perspective, front, back, left, top, bottom and back perspective views thereof in a condition that the claimed design has been completely unfolded. Reproductions **1.24** and **1.25** are reference photos showing the condition that the claimed design has been completely unfolded and the user is using the claimed design as a walking assistance equipment while wearing the wearable walking aid apparatus, and form no part of the claimed design. This design is for a cart on which the user can mount a wearable walking aid apparatus for rehabilitation of human lower body. This can also be used as a chair for wearing the wearable walking aid apparatus in a completely folded state,

as shown in reproduction **1.9** and as a walking assistance equipment in unfolded state as shown in reproduction **1.25**.
